SNAP HOOK

Edmond T. Blazewicz, Chicago, Ill.

Application April 20, 1951, Serial No. 222,077

7 Claims. (Cl. 24—233)

1

This invention relates to new and useful improvements in snap hooks generally, and is directed to subject matter similar to my co-pending application, filed December 2, 1949, Serial No. 130,714, now Patent No. 2,560,550, issued July 17, 1951.

The primary object of this invention is to provide a snap hook in which the latching member or tongue normally closing the same may be opened by pressing the same with a ring or the like to which a snap hook is to be secured, and which tongue may be positively urged to the open position to release the member to which a snap hook is attached.

Another important object of this invention is to provide a snap hook of this character, which when open, the tongue thereof will not interfere with the free movement of a ring or the like into or out of the hook.

Still another important object of the present invention is to provide a snap hook which is of simple and economical construction, and yet which will be durable and efficient for the purposes intended.

An important feature of the present invention resides in the provision of tongue shields at the juncture of the body member at the hook for receiving the tongue when the latter is in the open position.

Another important feature of the present invention resides in the provision of cam means for positively opening the tongue, and which means are efficaciously actuated by the sleeve slidably on the body member.

A further feature of the present invention resides in the novel manner in which the sleeve return spring is mounted and connects the body member and the sleeve.

Other objects and features of the present invention will become evident as the description thereof proceeds, a preferred embodiment of which has been illustrated by way of example only in the accompanying drawings, wherein:

Figure 1 is a side elevational view of the present invention;

Figure 2 is a vertical sectional view of the present invention taken substantially upon the plane of the section line 2—2 of Figure 1;

Figure 3 is another vertical sectional view of the present invention, this view being taken at right angles to the view shown in Figure 2, and in which the alternative open position of the tongue and the sleeve is shown in dotted outline;

Figure 4 is a horizontal sectional view taken upon the plane of the section line 4—4 of Figure 3, and showing certain concealed portions in dotted outline;

2

Figure 5 is an enlarged sectional detail view of the means provided for urging sliding movement of the sleeve on the body member; and

Figure 6 is an exploded side elevational view of the present invention.

Reference is now made more specifically to the accompanying drawings, wherein like numerals designate similar parts throughout the various views, and in which the numeral 10 designates

10 the snap hook generally.

The snap hook 10 comprises an elongated, hollow body member 12 having a hook 14 formed at one end thereof. A tongue 16 is positioned in the hollow body member 12 and is pivoted adjacent its inner end on a pivot pin 18 carried by the body member 12 so that the outer end 20 may be moved into and out of engagement with the free end 22 of the hook 14, as clearly shown by the dotted and full line positions of the tongue 16 shown in Figure 3.

In order to resiliently urge the tongue 16 into the hook closing full line position shown in Figure 3, the inner end of the tongue 16 and the inner surface of the body member 12 are provided 25 with opposed protuberances 24 and 26, respectively, and a coiled compression spring 28 is provided, the opposite ends of which are seated about the protuberances 24 and 26 to urge the same apart, thereby urging closing movement of the tongue 16.

30 It is to be particularly noted that when the tongue 16 is moved into the dotted line position shown in Figure 3, that the outer end 20 of the tongue 16 is received between tongue shields 30 formed on opposite sides of the body member 12

35 at the juncture of the body member 12 with the hook 14, and which shields 30 have smoothly curved edges 32. It will be readily appreciated that when the tongue 16 is moved into the dotted line position shown in Figure 3 that by virtue

40 of the fact that the outer end 20 of the same is received between the tongue shields 30, the tongue 16 cannot interfere with the introduction or removal from the snap hook of any object such as a ring or the like that the same may be secured to.

As thus far described, it will be understood that an object such as a ring or the like may be engaged by the snap hook by simply pressing such object against the free end 20 of the tongue 16 to move the same into the dotted line position shown in Figure 3, and that upon further movement of such an object toward the end of the hook 14 remote from the body member 12 the tongue 16 snaps to the full line position shown in Figure 3 under the action of the spring 28 to retain the same within the hook 14. Means is provided to positively open the tongue

16 which includes a sleeve 34 slidably positioned on the body member 12. A cross bar or pin 36 extends transversely through the sleeve 34, and the pin 36 slides in longitudinal slots 38 provided in the opposite sides of the body member 12 during longitudinal sliding movement of the sleeve 34 on the body member 12. As best shown in Figure 3, the pin 36 extends across the hollow interior of the body member 12 and is engageable with a cam surface 40 provided on the tongue 16 during sliding movement in the slots 38, it being evident from the drawings that upon movement of the sleeve 34 towards the hook 14 the tongue 16 will be moved from the full line to the dotted line position through the action of the pin 36 engaging the cam surface 40.

Means is provided to yieldingly urge the sleeve 34 to a position permitting the tongue 16 to close the hook 14, such means comprising the body member 12 having a longitudinal groove or recess 42 that opens at the end of the body member remote from the hook 14 and a protuberance 44 provided in the recess 42 to constitute a spring seat for the upper end of a coil compression spring 46 that extends downwardly in the recess 42. As best shown in Figure 5, the sleeve 34 is provided with an inwardly extending finger 48 that carries a protuberance 50 that constitutes a spring seat for the lower end of the spring 46 and which is in axial alignment with the protuberance 44, the arrangement being such that the sleeve 34 is urged downwardly with respect to the body member 12. It will be noted that during upward sliding movement of the sleeve 34 that the finger 48 and the protuberance 50 ride upwardly in the recess 42.

A swivel link 52 is secured to the end of the body member 12 by means of a pin 54, the swivel link 52 being provided with a shoulder 56 to limit downward sliding movement of the sleeve 34. A swivel 58 is secured to the swivel link 52 by means of a rivet 60, the rivet being retained in position in the link 52 by means of the pin 54 passing therethrough as will be understood.

The body member 12 and the sleeve 34 are preferably rectangular or square in cross section as shown in Figure 4, and in this connection, it is to be noted that the sides of the body member parallel to the pivotal movement of the tongue 16 are thickened considerably from the end of the body member nearest the hook 14 to a position adjacent the pivot pin 18 so as to constitute guiding surfaces for the pivotal movement of the tongue 16. It will be observed that it is into the thickened portions of the walls that the recess 42 extends so as to constitute with the sleeve 34 a socket for the upper end of the spring 46.

The construction and operation of the invention has been set forth in considerable detail so that the principles thereof may be readily utilized by others, it being understood that the spirit of the invention is subject to modifications that lie within the scope of the appended claims.

It will now be seen that there has been provided a snap hook which may be conveniently secured to an object, and just as readily released by simply sliding a sleeve toward the hook, the outer surface of the sleeve being serrated to facilitate this operation.

Having described the invention, what is claimed as new is:

1. A snap hook comprising an elongated hollow body member having a hook formed at one end thereof, an elongated tongue having its inner end received in the body member and its outer end normally engaging and closing the hook,

means adjacent the inner end of the tongue swingably securing the tongue to the body member, said tongue being swingable to disengage and open the hook, means yieldingly urging engagement of the tongue and the hook, means for opening the hook comprising a sleeve slidably mounted on the body member, said sleeve having a pin extending transversely therethrough, said body member having a longitudinal slot slidably receiving the pin, said tongue having a cam surface that is engaged by the pin to disengage the tongue and the hook upon movement of the sleeve in one direction, and means yieldingly urging movement of the sleeve in the opposite direction.

2. A snap hook comprising an elongated hollow body member having a hook formed at one end thereof, an elongated tongue received in the body member and pivoted adjacent its inner end thereto, the outer end of the tongue being movable to selectively open and close the hook, means yieldingly urging closing movement of the tongue, means for urging opening movement of the tongue comprising a sleeve slidably longitudinally on the body member and having a pin extending transversely therethrough, said body having a longitudinal slot slidably receiving the pin, said tongue having a cam surface that is engaged by the pin to open the hook upon sliding movement of the sleeve in one direction, and means yieldingly urging sliding movement of the sleeve in the other direction.

3. A snap hook comprising an elongated hollow body member having a hook formed at one end thereof, an elongated tongue received in the body member and pivoted adjacent its inner end thereto, the outer end of the tongue being movable to selectively open and close the hook, means yieldingly urging closing movement of the tongue, means for urging opening movement of the tongue comprising a sleeve slidably longitudinally on the body member and having a pin extending transversely therethrough, said body having a longitudinal slot slidably receiving the pin, said tongue having a cam surface that is engaged by the pin to open the hook upon sliding movement of the sleeve towards the hook, means yieldingly urging movement of the sleeve towards the other end of the body member.

4. A snap hook comprising an elongated hollow body member having a hook formed at one end thereof, an elongated tongue received in the body member and pivoted adjacent its inner end thereto, the outer end of the tongue being movable to selectively open and close the hook, means yieldingly urging closing movement of the tongue, means for urging opening movement of the tongue comprising a sleeve slidably longitudinally on the body member and having a pin extending transversely therethrough, said body having a longitudinal slot slidably receiving the pin, said tongue having a cam surface that is engaged by the pin to open the hook upon sliding movement of the sleeve towards the hook, means yieldingly urging movement of the sleeve towards the other end of the body member, and means at the other end of the body member for attaching the same to a line and also for limiting movement of the sleeve towards said other end of the body member.

5. A snap hook comprising an elongated hollow body member having a hook formed at one end thereof, an elongated tongue received in the body member and pivoted adjacent its inner end thereto, the outer end of the tongue being movable to

selectively open and close the hook, means yieldingly urging closing movement of the tongue, means for urging opening movement of the tongue comprising a sleeve slidable longitudinally on the body member and having a pin extending transversely therethrough, said body having a longitudinal slot slidably receiving the pin, said tongue having a cam surface that is engaged by the pin to open the hook upon sliding movement of the sleeve in one direction, and means yieldingly urging sliding movement of the sleeve in the other direction.

6. A snap hook comprising an elongated hollow body member having a hook formed at one end thereof, said body member including spaced tongue shields adjacent the juncture of the hook and the body member, an elongated tongue received in the body member and pivoted adjacent its inner end thereto, the outer end of the tongue being movable from a sheltered hook-opening position between the tongue shields to engage the hook closing the same, means yieldingly urging closing movement of the tongue, means for urging opening movement of the tongue com-

prising a sleeve slidable longitudinally on the body member and having a pin extending transversely therethrough, said body having a longitudinal slot slidably receiving the pin, said tongue having a cam surface that is engaged by the pin to open the hook upon sliding movement of the sleeve in one direction, and means yieldingly urging sliding movement of the sleeve in the other direction.

7. The combination of claim 6, wherein said first means includes a compression spring seated between the body member and the inner end of the tongue.
